UNITED STATES PATENT OFFICE.

EDWARD THOMAS MORRIS AND THOMAS JOSEPH MILLS, OF LONDON, ENGLAND, AS
SIGNORS, BY MESNE ASSIGNMENTS, TO R. HOE & CO., INC., OF NEW YORK, N. Y.,
A CORPORATION OF NEW YORK.

PRINTING SEAL OR EDITION HEADINGS AND LATE OR STOP-PRESS NEWS.

Application filed April 6, 1923. Serial No. 630,210.

To all whom it may concern:

Be it known that we, EDWARD THOMAS MORRIS and THOMAS JOSEPH MILLS, both subjects of the King of Great Britain, residing at 109 Borough Road, London, England, have invented new and useful Improvements in Printing Seal or Edition Headings and Late or Stop-Press News, of which the following is a specification.

10 Heretofore the cylinders for printing seal or edition headings and late or stop press news have usually been slidably mounted upon a rotating shaft and supplied with ink by separate inking mechanism slidably supported on a stretcher bar extending across the printing machine. With such an arrangement the position of the edition headings or late news cylinders could only be altered within certain limitations. It was 15 not possible, for example, to print the edition heading and late news in the same column of a paper in different colours nor in adjacent columns, nor could the edition heading cylinder, if arranged to print on 20 the left of the late news cylinder, readily be transferred so as to print on the right of the late news cylinder and vice versa.

In another usual method of printing edition headings and late news, a single cylinder was employed to print the edition heading and the late news in adjacent columns, the inking mechanism for the edition heading, and the inking mechanism for the late news, being combined and carried on 25 the same support. With this arrangement also it was impossible to print the edition heading and the late news in the same column in different colours. Moreover, if the edition heading was originally printed 30 on the left of the late news, the cylinder could not readily be altered so as to print it on the right, and vice versa.

The main object of our invention is to provide means whereby the edition heading 35 and the late news can be printed in the same column in two different colours.

According to our invention the cylinders for printing the edition headings and the late news are slidably mounted upon separate shafts spaced a sufficient distance apart to enable the cylinders to be moved past one another, and the inking mechanisms for supplying the cylinders are also supported on a stretcher bar or bars in such a

manner that they can also be moved past one another.

In one way of carrying out our invention the inking mechanisms are supported one on either side of a stretcher bar which may conveniently be of U or box girder form having on each side a slot to receive the bolts by means of which the inking mechanism is secured, the said stretcher bar being located between the shafts carrying the cylinders. With this arrangement the seal or edition heading can be printed in any position on any page across the impression cylinder, and the late or stop press news can also be printed in any position on any page across the impression cylinder, and further the seal or edition heading and the late or stop press news can if desired be printed in the same column in two different colours.

The accompanying drawing, which shows 75 those parts of a printing machine necessary to illustrate the invention, is an end elevation partly in section.

1 is an impression cylinder, 2 a cylinder for printing edition headings and 3 a cylinder for printing late news. The cylinders 2 and 3 are slidably mounted upon shafts 4, 5, spaced a sufficient distance apart to enable the cylinders 2, 3, to be moved past one another. Located between the cylinders 2 and 3 is a stretcher bar 6 in each side of which a T shaped slot 7 is provided. 8, 9, are frames carrying the usual inking mechanism for the cylinders 2 and 3 respectively. The frames 8, 9, are slidably secured one on either side of the stretcher bar 6 by bolts 10, the heads of which engage the T shaped slots 7.

In operation the cylinders 2 and 3 are slid 85 den and secured in any desired position on their shafts 4, 5, and the frames 8, 9, and inking mechanism are slid along the stretcher bar 6 into position for inking the cylinders 2, 3, and secured in position by the bolts 10.

What we claim is:—

1. In a printing machine, the combination 95 of a shaft, a cylinder for printing edition headings slidably mounted thereon, a second shaft, a cylinder for printing late news slidably mounted on the second shaft, the said shafts being spaced a sufficient distance apart to enable the cylinders to be moved 100 105

past one another, separate inking mechanisms for supplying the cylinders and means for supporting the inking mechanisms in such a manner that the said inking mechanisms can be moved past one another.

2. In a printing machine, the combination of a shaft, a cylinder for printing edition headings slidably mounted thereon, a second shaft, a cylinder for printing late news slidably mounted on the second shaft, the said shafts being spaced a sufficient distance apart to enable the cylinders to be

moved past one another, a stretcher bar, inking mechanism for supplying one of the cylinders slidably mounted on one side of the stretcher bar, and inking mechanism for supplying the other cylinder slidably mounted on the other side of the stretcher bar.

In testimony that we claim the foregoing as our invention we have signed our names this 26th day of March, 1923.

EDWARD THOMAS MORRIS.
THOMAS JOSEPH MILLS.
